COVER PLATE FOR A COMBINATION LOUD SPEAKER, VENTILATOR, AND LIGHTING FIXTURE

Josef J. Hammes, Maplewood, Mo., assignor to
Benjamin W. Lowell, St. Louis County, Mo.

Filed Feb. 23, 1961, Ser. No. 64,036

Term of patent 14 years

(Cl. D62—4)

Fig. 1.

Fig. 2.

Fig. 3

FIGURE 1 is a side elevational view of a cover plate for a combination loud speaker ventilator, and lighting fixture, showing my new design;

FIGURE 2 is a top plan view; and

FIGURE 3 is a phantom outline taken on line 3—3 of FIGURE 2.

I claim:

The ornamental design for a cover plate for a combination loud speaker, ventilator and lighting fixture, as shown.
